Attorney.

UNITED STATES PATENT OFFICE.

JAMES BLAINE WALKER, OF NEW YORK, N. Y.

WINDOW CLARIFIER.

Application filed March 15, 1928. Serial No. 261,806.

This application is a continuation in part of my application Serial No. 200,551, filed June 22, 1927.

This invention relates particularly to means for keeping clear the windows of cabs of engineers and motormen operating locomotives, cars and other vehicles, propelled by steam, electricity or other power, wherein the engineer sits or stands behind a window 10 through which he must look to obtain a clear view head.

Objects of this invention are to provide an effective means which is inexpensive both in first cost and in operation for clearing such 15 windows and for keeping them clear, and for preventing the accumulation of frost or snow thereon, the means being such that the operation will take but little of the engineer's time and will not distract him from his main 20 duties or require that he leave his position within the cab. Further objects are to provide a construction which is easy to operate, and the operation of which will not be obstructed by the adhesion of frost to the 25 surface of the pane.

In the accompanying two sheets of drawings which form a part of this description,

Figure 1 is a vertical section through a panel or section of the front wall of a car 30 or engineer's cab taken on the line I—I of Fig. 3, which includes a window-frame with this invention embodied.

Fig. 2 is a vertical section through the same on the line II—II of Fig. 3.

Fig. 3 is an elevation viewed from the inside of the car or cab.

Fig. 4 is a horizontal section to a larger scale on the line IV—IV of Figs. 5 and 6.

Fig. 5 is a vertical section of a portion 40 on the line V—V of Fig. 4.

Fig. 6 is a vertical section of a portion on the line VI—VI of Fig. 4.

The front wall of the car or engineer's cab has a window-frame with two pairs of guides 45 7, 7 and a pocket 8. Window sashes 9, 9 with panes 10, 10 slide in the guides and either can be lowered into the pocket. A handle 11 on the top bar of the inner sash is provided for directly raising and lowering this 50 sash. Chains 12, 12 lead over pulleys 13, 13 and connect the top bars of the two sashes so that on raising or lowering the inner sash by means of its handle the outer sash will be reversely lowered or raised, and either sash

may be used to close the window opening 55 while the other is in the pocket. Interconnection of the sashes, however, is not essential.

At the mouth of the pocket are wipers 14, 14 each consisting of a clamp which holds 60 a soft rubber strip with one edge projecting from the jaws of the clamp. The wipers are mounted to fold about their rear edges. For this purpose and to stiffen the wipers, rods 15, 15 are attached to these edges. The ends 65 of these rods engage hinge holes in nuts 16, 16 which are carried on screws 17, 17 by which the wipers are set to a proper adjustment when they are horizontal for bearing against and wiping the panes. The wipers have 70 crank-pins 18, 18 which are connected through links 19, 19 with a hand lever 20 by which either wiper can be moved out of engagement with its pane and the other wiper moved into engagement with its pane. The movement 75 into and out of engagement is independent of the screws so that on return to its horizontal position the wiper will be restored to the same adjustment.

It is not necessary to wipe each pane both 80 when it is being lowered into the pocket and when it is being withdrawn and by wiping during movement in only one direction, only one pane will be wiped as the positions of the panes are exchanged and the panes are more 85 easily changed. Furthermore, there may be an adhesion of frost or snow to the exposed pane which would interfere with the sliding of the pane past the wiper if the wiper were in engagement with the pane while it is being lowered into the pocket, and the wiper is therefore folded out of engagement during such movement. But while the pane is in the pocket any such frost or snow which may be adhering will be loosened or converted to 90 moisture and will be readily wiped off as the pane is brought out of the pocket into operative position.

Latches 21, 21 engage ratchets in the edges 100 of the sashes, and each latch by engagement with its sash keeps the sash from being lowered into the pocket. Pins 22, 22 project from the latches and are engaged by cams 23, 23 which are formed on the hand lever and operate when the lever is in one position 105 to retract one latch and permit the lowering of the sash which it engages, this being also the position of the hand lever which folds

the wiper for the pane of the sash down and out of engagement while the sash is released for lowering. Since the latches make a ratchet connection, neither latch interferes 5 with the lifting of the sash which it engages.

An electrical heating element 25 is provided in the pocket and serves to heat which-ever pane is in the pocket.

In operation, when the engineer or motor-10 man finds that the pane through which he is looking is tending to become obscured by the lodgement of particles of dust, or is likely to become obscured by the accumulation of frost or snow, he raises or lowers the inner sash 15 according as it is down or up and thereby exchanges the position of the sashes and brings out of the pocket the pane that he is to look through. By reason of its warmth, frost or snow will not commence to accumulate there-20 on until it has had time to cool off and before such time arrives the places of the panes are again exchanged.

Application of wipers as set forth is not limited to the outer side of the panes, but a 25 hand wiper can be readily used to remove particles of dust or moisture on the inner sides of the panes which face the engineer or motorman.

I claim:

30 1. A window-frame provided with a pocket, a transparent pane slidable into and out of the pocket, a wiper for the pane supported by the frame at the mouth of the pocket and movable into and out of engagement with the

35 pane, means for preventing the movement of the pane into the pocket, and means operating with the movement of the wiper out of engagement with the pane for withdrawing the means for preventing the movement of the 40 pane into the pocket.

2. A window-frame provided with a pocket, a transparent pane slidable into and out of the pocket, a wiper for the pane supported by the frame at the mouth of the pocket and 45 movable into and out of engagement with the pane, means for preventing the movement of the pane into the pocket, means for preventing the withdrawal of the pane out of the pocket, means operating with the movement 50 of the wiper out of engagement with the pane for withdrawing the means for preventing the movement of the pane into the pocket, and means operating with the movement of the wiper into engagement with the pane for

withdrawing the means for preventing the 55 withdrawal of the pane from the pocket.

3. A window-frame provided with a pocket, a transparent pane slidable into and out of the pocket, a wiper for the pane supported by the frame at the mouth of the pocket and 60 movable into and out of engagement with the pane, a latch for preventing the movement of the pane into the pocket, and means operating with the movement of the wiper out of engagement with the pane for withdrawing 65 the latch.

4. A window-frame provided with a pocket, a transparent pane slidable into and out of the pocket, a wiper for the pane supported by the frame at the mouth of the pocket and 70 movable into and out of engagement with the pane, a latch for preventing the withdrawal of the pane from the pocket, a latch for preventing the movement of the pane into the pocket, means operating with the movement 75 of the wiper into engagement with the pane for withdrawing the latch which prevents the withdrawal of the pane from the pocket, and means operating with the movement of the wiper out of engagement with the pane 80 for withdrawing the latch which prevents movement of the pane into the pocket.

5. A window-frame provided with a pocket, a transparent pane slidable into and out of the pocket, a wiper for the pane supported by the frame at the mouth of the pocket, means for adjusting the wiper to the pane, and a hinge connection between the wiper and the adjusting means whereby the wiper 85 can be folded into and out of engagement 90 with the pane without altering the adjustment.

6. A window-frame provided with a pocket, two panes slidable into and out of the pocket, pulley connections between the panes 95 whereby when one pane is moved into the pocket the other pane is withdrawn from the pocket, a wiper for each pane, a latch for preventing the movement of each pane into the pocket, means for moving either wiper 100 into engagement with its pane, means for simultaneously moving the other wiper out of engagement with its pane, and means for simultaneously retracting the latch which prevents movement of the pane into the 105 pocket from which the wiper has been moved out of engagement.

JAMES BLAINE WALKER.
